UNITED STATES PATENT OFFICE.

ALPHEUS BUELL ROBBINS, OF MEDFORD, OREGON.

PRUNING-KNIFE.

1,133,886.

Specification of Letters Patent.

Patented Mar. 30, 1915.

Application filed July 25, 1914. Serial No. 853,098.

To all whom it may concern:

Be it known that I, ALPHEUS BUELL ROBBINS, a citizen of the United States, residing at Medford, in the county of Jackson 5 and State of Oregon, have invented certain new and useful Improvements in Pruning-Knives; and I do hereby declare the following to be a full, clear, and exact description of the invention, such as will enable 10 others skilled in the art to which it appertains to make and use the same.

This invention relates to new and useful improvements in pruning knives, and has for its principal object to provide a knife 15 which is particularly adapted for use on trees and similar plants wherein the bark is apt to become affected.

Another object of the invention is to provide a simple and effective knife in which a 20 plurality of tools is combined, thus avoiding the necessity of the possessor having a number of tools.

A further object of the invention is to provide a knife in which the blade is constructed of a single piece of sheet metal 25 thus avoiding the necessity of welding or otherwise attaching the several different portions of the knife together.

With these and other objects in view, the 30 invention consists in the novel combination and arrangement of parts which will be fully set forth in the following specification and accompanying drawings, in which,

Figure 1 is a perspective view of the knife 35 constructed in accordance with this invention. Fig. 2 is a view similar to Fig. 1 from the opposite side, and Fig. 3 is a sectional view taken on line 3—3 of Fig. 1.

Referring now to the drawings by characters of reference, the numeral 1 designates 40 as an entirety the handle portion of the knife comprising the usual gripping members 2 and 3, which are riveted or otherwise secured to the handle portion of the blade 45 4 as at 5.

Formed integral with the handle portion of the blade is the blade portion designated

generally by the numeral 6 which comprises the main body portion 7 having formed thereon the lateral extension 8. This blade 50 is sharpened on both edges as at 9 and the lateral extension is also sharpened on its inner edge as at 10. An angular extension 11 is formed at the free terminal of the blade, and said angular extension is provided 55 with the sharpened edges 12 and 13 which are arranged to coöperate when the device is in use.

It will be apparent from the foregoing that in use the curved portion of the knife 60 where the angular extension 11 joins the blade 7, may be used as a gouge in order that the user may determine whether or not a tree is in need of treatment. The straight edge 13 is used to scrape the wood after 65 the bark has been removed when a tree is in need of treatment and the point formed where the edges 12 and 13 meet is to remove the bark and also to scrape the under parts of the roots of the tree when the same is 70 affected. The hook-shaped extension 8 is particularly adapted for use in trimming and cutting off of small limbs and also to reach in the crotch between limbs to permit the user to scrape the wood to remove any 75 disease.

From the foregoing it will be apparent that an exceedingly useful tool is provided which will eliminate the necessity of using or having in the user's possession a number 80 of tools, and also a simple and compact device is provided.

While in the foregoing there has been shown and described the preferred embodiment of this invention, it is to be understood 85 that such changes may be made in the combination and arrangement of parts as will fall within the spirit and scope of the invention as defined in the appended claim.

Having thus described my invention, I 90 claim:

A pruning knife including a handle, a blade secured to the handle, said blade being sharpened on both edges, an angular ex-

tension at the free end of the blade, the free end of the angular extension being inclined and sharpened, the angular extension and blade forming a gouge, and a lateral projection formed near the free end of the blade, said lateral projection being provided with a sharpened edge arranged to coincide with the sharpened edge of the blade to

form a means whereby limbs may be cut from a tree.

In testimony whereof I affix my signature in presence of two witnesses.

ALPHEUS BUELL ROBBINS.
